UNITED STATES PATENT OFFICE.

HENRY FERDINAND DEMMER, OF BALLINGER, TEXAS.

ALARM.

Application filed February 28, 1923. Serial No. 621,822.

To all whom it may concern:

Be it known that I, HENRY F. DEMMER, a citizen of the United States, residing at Ballinger, in the county of Runnels and State of Texas, have invented certain new and useful Improvements in Alarms, of which the following is a specification.

This invention relates to automatically sounding alarms and its primary object is to provide a simple and efficient mechanism whereby, when the door of a garage or like structure is opened, an alarm will be sounded and notice thereby given so that, if the opening is unauthorized, the intrusion will be at once detected. The invention is intended primarily for use to prevent theft of automobiles and is so arranged that, when the door of a garage is opened, the horn of the automobile will be sounded. The invention includes means for holding the alarm inoperative while the door of the garage is open and the garage is occupied by the owner of the vehicle or other authorized persons, the said means being so arranged as to be released when the door is closed and the alarm thereby set for operation. The stated objects of the invention, and other objects which will hereinafter incidentally appear, are attained in such a device as is illustrated in the accompanying drawing, and the invention resides in certain novel features which will be particularly pointed out in the appended claims.

In the drawing:

Figure 1 is a view, partly in plan and partly in horizontal section, showing my improved alarm as arranged in a garage, and

Fig. 2 is an enlarged perspective view of the operating parts of the alarm showing them as they are arranged when the garage is to be occupied without the alarm sounding.

In the drawing, the reference numeral 1 indicates a portion of a garage and 2 a portion of an automobile therein equipped with a horn 3 which may be of any well-known or preferred type operated from the battery or magneto of the car. In carrying out my invention, I provide within the garage a bracket or supporting plate 4 which may be secured in any convenient manner at a point in or adjacent the horizontal plane of the upper end of the door 5. Extending through and rigidly secured in the said supporting plate are terminals 6, to which are attached conductors 7 and 8 (see Fig. 2) which are to be connected with the horn and battery

of the automobile so that if a circuit be closed through the terminal 6 the horn will be sounded just as though in use upon the road. One of the terminals 6 constitutes the fulcrum or pivot for a circuit-closing lever 9 which extends to both sides of said terminal and has a spring 10 attached thereto near one end, the opposite end of the spring being secured in any convenient manner to the supporting plate 4, as will be most readily understood upon reference to Fig. 2. The lever 9 may be of any convenient form and is illustrated as constructed from a single strand of stout wire having its ends brought together, as shown at 11, and having eyes 12 formed at intermediate portions of its length to encircle the fulcrum terminal. The fold or bight produced in the wire by bringing its ends together presents a somewhat widened surface which may be engaged by a latch 13 or by an operating bracket 14, as the case may be. The latch 13 is pivotally engaged upon a loop or other fixed support 15 depending from the supporting plate 4 and, in the present instance, is provided with a notch 16 in its free end adapted to engage partly around one branch of the circuit-closing lever 9. The bracket 14 is secured rigidly to the door 5 near the free edge thereof and near the upper end of the same in position to impinge against the end of the circuit-closing lever when the door is closed.

When it is desired to perform any work within the garage or for other reason the garage is to be occupied or the door left open and it is desired to prevent sounding of the alarm, the latch 13 is swung into position to engage the wider operating or handle end of the lever 9, as shown in Fig. 2, and the length of the latch is such that, when it so engages the lever, the spring-attached end thereof will be held out of contact with the adjacent terminal 6 against the tension of the spring 10 so that the circuit through the lever will be broken, the spring acting upon the lever with sufficient force to hold it in engagement with the latch so that the latch will be gripped by and between the lever and the loop 15 and the contact end of the lever will be maintained out of engagement with the terminal, as will be readily understood. It will be noted that the bracket 14 has one end turned downwardly, as shown at 17, whereby it may be rigidly secured to the door and the opposite end of the bracket is turned upwardly, as shown at 18, to provide an

abutment or lever-striking lip which will project into the path of the lever 9. The bracket or switch-throwing arm 14 is so arranged and of such length that, when the door is fully closed, the bracket will pass beside the latch and the lip or striker 18 will project beyond the end of the latch 13 and will impinge against the lever and swing the same slightly about its pivot, whereupon the latch will be released and will drop into the position shown in dotted lines in Fig. 2, the spring 10 being put under greater tension and the contact end of the lever being moved a slightly greater distance from the adjacent terminal 6. If the door be then opened, the bracket will be withdrawn whereupon spring 10 will contract and at once draw the contact end of the lever against the adjacent terminal 6 so that the circuit will be closed and the horn of the automobile sounded, the horn continuing to sound until the circuit is again broken. Obviously, if the opening of the garage is by some unauthorized person, the owner or occupants of the adjacent dwelling will at once become aware of the intrusion and may take such action as will result in the arrest of the intruder and prevention of the threatened theft of the automobile. The attachment of the conductors 7 and 8 with the horn and the body of the automobile are, of course, detachable so that, when the automobile is to be used, they may be readily separated from the car. If so desired, the device may be connected with a bell 22 and a switch 23 in the dwelling so that in the night time if the switch 23 be closed and the door of the garage should then be opened, the alarm will be sounded in the dwelling and the occupants notified of the conditions.

My device is exceedingly simple in the construction and arrangement of its parts,

it may be very readily applied to any garage at a very slight expense, and will prove highly efficient in use for the purposes for which it is designed.

Having thus described the invention, what is claimed as new is:

1. In an alarm, the combination of fixed electric terminals, a switch lever fulcrumed upon one of the terminals and extending past the other terminal, yieldable means connected with the lever and tending constantly to effect contact between the lever and said other terminal, means adapted to directly engage the switch lever and hold it out of contact with said other terminal in opposition to said yieldable means, and means carried by a moving part to directly engage the lever and release it from said holding means and maintain the lever out of contact with said terminal. 50 55 60

2. In a device for the purpose set forth, the combination of spaced electric terminals, a switch lever fulcrumed upon one of said terminals and adapted to form contact with the other terminal, a spring acting upon the contact end of the switch lever to move it into engagement with the adjacent terminal, a pivoted gravity latch adapted to engage the opposite end of the lever and thereby hold the lever out of contact with the said terminal, and a bracket secured to a moving part and adapted to impinge against the lever adjacent the point of engagement of the latch therewith whereby to release the switch lever from the latch and increase the distance between the lever and the adjacent terminal, the withdrawal of the bracket permitting the lever to make contact with the terminal. 65 70 75 80

In testimony whereof I affix my signature.

HENRY FERDINAND DEMMER. [L. S.]
